UNITED STATES PATENT OFFICE.

ANTONIO GUSTIANA, OF SUDBURY, ONTARIO, CANADA.

STEERING APPARATUS FOR AIR-CRAFT.

1,118,124.

Specification of Letters Patent.

Patented Nov. 24, 1914.

Application filed June 7, 1913. Serial No. 772,293.

To all whom it may concern:

Be it known that I, ANTONIO GUSTIANA, a citizen of the United States of America, residing at the town of Sudbury, in the district of Algoma and Province of Ontario, Dominion of Canada, have invented certain new and useful Improvements in Steering Apparatus for Air-Craft; and I hereby declare that the following is a full, clear, and exact description of the same.

My invention relates to steering apparatus for aerial craft, in which the rudder is journaled in an oscillating bearing so that it can be turned in any direction with respect to the longitudinal axis of the aerial craft for causing the aerial craft to fly in the direction required by the aerial navigator, as hereinafter set forth and particularly pointed out in the claim.

In the drawings: Figure 1, is a perspective view of the rudder and its related parts in their normal position; Fig. 2, is a plan view of the same, showing the normal position of the rudder in full lines and its turning positions in dotted lines when changing the direction of the aerial craft to the right or left; Fig. 3, is a side elevation showing the normal position of the rudder in full lines and its turning positions in dotted lines when causing it to assume an upward or downward inclination and Fig. 4, is a front elevation of the steering apparatus.

Like characters of reference refer to like parts throughout the specification and drawings.

The rudder *a* is fixed on a shaft *b* journaled in an oscillating bearing *c*, and fixed on the shaft *b* is a drum *d*, to which are connected tiller ropes *e* whereby said rudder can be caused to oscillate around the axis of the shaft. The bearing *c* is provided with hollow arbors *f* rockably mounted in an oscillating frame *g*, the tiller ropes *e* passing through the hollow arbors *f* to the drum *d*. The oscillating frame *g* is provided with arbors *h* journaled in the forks *i* of the tail frame *j* and connected to the oscillating frame *g* are tiller ropes *k* operated from a tiller *l* conveniently fulcrumed to either the tail frame *j* or some other convenient part

of the air craft *j*. Connected to the oscillating bearing *c* are tiller ropes *m* by which the bearing *c* causes the rudder to oscillate around the axis of the shaft.

The operation of the steering apparatus is as follows:—Assuming that the air craft is advancing in a horizontal position, and it is desired to cause it to change its direction to the left—in this case, the tiller ropes *k* will be worked to turn the oscillating frame *g* so that the rudder *a* will assume an inclined position to the left of the longitudinal axis of the air craft *j* and tail frame *j*. The rudder, in this case, being in a perpendicular plane, will cause the head of the air craft to swing to the left. If it is desired to change the direction of the air craft to the right, the oscillating frame *g* and rudder *a* are turned to the right causing a corresponding change of the head of the air craft to the right. If it is desired to cause the air craft to fly downward, the tiller ropes *e* are operated to turn the rudder *a* to a horizontal position. The tiller ropes *m* are then operated to oscillate the bearing *c* and turn rudder *a* in a downward direction, these movements of the rudder causing the head of the air craft to assume a downward direction. If it is desired to cause the air craft to fly upward, the oscillating bearing *c* and rudder *a* are turned in an upward direction.

If it is necessary at any time to combine the upward and downward direction with a change of direction to the right or left, the rudder can be turned into a tilted position to the right or left of its longitudinal axis above or below its normal horizontal position.

Having thus fully described the nature of my invention, what I claim as new and desire to secure by Letters Patent, is:—

A steering apparatus for air craft, comprising a forked-tail frame, an oscillating annular frame journaled between the forks thereof, means for turning the oscillating frame about its axis, an oscillating annular bearing having hollow arbors journaled in the oscillating frame, whereby the axis of the revolution of the oscillating bearing is

at right angles to the oscillating frame, means for turning the oscillating bearing independently of the oscillating frame, a rotatable shaft journaled in the oscillating bearing, a rudder fixed on said shaft, a drum mounted on said shaft, and flexible means passing through the hollow arbors and connected with said drum for turning the shaft and rudder independently of the

oscillating bearing or frame whereby the rudder can be turned into a horizontal plane or into an angular relation therewith.

Sudbury, May 27th, 1913.

ANTONIO GUSTIANA.

Signed in the presence of—

GEO. J. VALIN,
L. H. MEHER.
